UNITED STATES PATENT OFFICE.

LINDSAY C. PRITNER AND HENRY C. DORRIS, OF JOHNSTOWN, PENNSYLVANIA.

METAL BENDING.

Application filed August 15, 1922. Serial No. 581,933.

To all whom it may concern:

Be it known that we, LINDSAY C. PRITNER and HENRY C. DORRIS, citizens of the United States, and residing in the city of Johnstown, county of Cambria, and State of Pennsylvania, have invented certain new and useful Improvements in Metal Bending; and we do hereby declare the following to be a full, clear, and exact description of the invention, such as will enable others skilled in the art to which it appertains to make and use the same.

Our invention relates to bending metal and to the dies and apparatus for performing some of the operations in shaping a plate of metal with particular reference to forming railway truck side frames of the type generally disclosed in United States Patent to G. A. Anderson, No. 1,422,074, dated July 11, 1922.

The type of truck side frame referred to is formed of one metal plate, and all the main members thereof are substantially integral, so that the entire truck side frame may be said to be composed of one piece of metal, shaped and formed in its various parts to provide the different members, each of which is adapted to perform its proper functions in use.

Prior operations in forming such a truck side frame may consist in taking a plate of metal, preferably of steel or iron, cutting it to shape, then forming flanges on various of its edges, and the present invention comprises bending the cut and flanged plate about its intermediate portion until the edges of the flanges are opposite; with the apparatus therefor.

After the steps above mentioned have been completed, the cut and flanged plate is placed on our bottom bending female die, which die is provided with a groove of open-box or U-section, the plate being arranged with its longitudinal intermediate portion above the longitudinally extending groove of the die. After the cut and flanged plate is accurately placed thereon in position, this position being determined by gauges or other stops suitably arranged on or adjacent our die, a male die which is substantially of the same length as the bottom die, but of narrower width by an amount about equal to twice the thickness of the plate to be bent, is projected against the plate and forced

downwardly, thereby bending the plate about its intermediate portion until the two sides are opposite each other, but at a small angle with each other.

The female die may be fixed while the male die is movable, or vice versa, or both may be movable as will be readily understood.

The lower edge of the upper die is provided with a removable former of one piece or preferably a pair of wedge-shape portions, which, when placed together and temporarily secured thereon have the form which is desired to be given to the interior of the intermediate bent portion of the frame. The detailed construction of this former will be explained hereafter in more detail.

After the top die has reached the limit of its travel and has pressed the intermediate portion of the plate into the groove of the bottom die, whereby it assumes the form of said bottom die, the pressure on the top die is slightly released and the main portion of the top die withdrawn, leaving the former within the pressed or bent portion of the frame, which portion eventually forms the top arch bar member of the truck side frame.

After this is done the frame is placed in another set of dies, which close the side portions together, making them parallel, but this does not form any part of the present invention, and is the subject of another application, for pressing metal, filed August 15, 1922, Serial No. 581,932.

Having thus given a general description of our invention, we will now, in order to make the matter more clear, refer to the annexed sheet of drawings, which form part of this specification, and in which like characters refer to like parts:—

Figure 1 is a side elevation of our bending dies with a pressed metal truck side frame, previously flanged and partially formed, in position on the lower die just before it is bent centrally; Fig. 2 is a bottom plan view of the top bending die with the removable former of wedge shapes in place thereon; Fig. 3 is an end elevation of the bending dies shown in position at the end of the working stroke of the top die; Fig. 4 is a vertical central sectional elevation through a pressed metal truck side frame after being bent by our dies and with

the removable former in place therein, and Fig. 5 is a section through the former taken on the line V—V of Fig. 2.

Referring now to the characters of reference on the drawings:—1 is the top die holder, which may be secured to the platen or plunger of a hydraulic or other press having a stroke of sufficient length and power to perform the operations desired. 2 is a groove or slot in the upper die holder adapted to receive the upper edge portion of the top die 4, which is secured therein by means of the bolts 3. I provide grooves on each side of the top die, namely, 5, 6, 7 and 8, of widths, lengths and depths sufficient to receive the corresponding flanges of the previously flanged plate, so that when the two portions of the plate are bent toward each other the flanges enter these grooves and allow the bending to proceed without obstruction or deformation of the plate. I also provide projections 9 within the groove 8 which are preferably formed integral with the top die 4, and below these I provide reinforcing blocks 10, which are adapted to back up the former 21 and prevent it from bending or distortion during the operation. These blocks 10 may be integral or may be separate and secured in place by tap bolts 30 or otherwise. At the ends of the top die 4 I provide brackets or clevises 11 which are secured in position by the tap bolts 12, the lower ends being bifurcated, with eyes 13, through which the pins 14 are passed, to temporarily secure the former 21 in position against the lower surface of the top die. The previously cut and flanged plate from which the truck side frame is formed is 15, while 16 represents the bottom die in general, which may be secured in place on the lower bed of the platen of the press and secured thereon by any desired means so that it accurately registers with the top die. The bottom die is provided with a groove 17, which is of open-box form with rounded corners or of U-shape, and this, together with the top die and former provides a matrix in which the top arch bar member of the truck side frame is accurately pressed to shape. The sides of the truck side frame are 18, and the inwardly extending flanged edges thereof are indicated as 19, while the central intermediate portions of the truck side frame which form the top arch bar member are 20.

It should be noted that the wedges 21 are tapered to some extent and when placed together they provide a parallel former of rectangular cross-section with rounded corners.

Having thus described our apparatus, we will now explain the method of operation:— When the top male die 4 is in the upward position as illustrated in Fig. 1, the previously cut and flanged metal blank 15 is

placed in position on the female bottom die, as illustrated, and accurately positioned thereon by means of stops or gauges (not shown). The plate may be either hot or cold, but preferably hot from previous operations. After this is done the top die 4 is caused to be moved downwardly, whereupon the lower surface of the former 21 contacts with the intermediate portion of the blank and presses it downwardly into the groove 17 of the bottom die, whereupon the sides of the blank rise up simultaneously with the corresponding parts of the symmetrical blank substantially opposite each other, as illustrated in Figs. 3 and 4. After this is done the pins 14 are removed, the top die 4 is withdrawn, and the bent plate 15 with the former 21 still therein is removed to another apparatus for further operation.

Although we have shown the former 21 made of two tapered pieces, we may also make this member of one piece of substantially parallel form, but this would require more force for its withdrawal. We therefore prefer to make this member of two wedge-shaped pieces, for the reason that as one of the wedges is started in its removal movement it at once releases the pressure and reduces the friction of withdrawal.

Either before or after the subsequent operation is performed, the wedges 21 may be withdrawn longitudinally, and to assist in loosening them the ends of one may project slightly beyond the other, so it may be struck with a sledge to start it, after which it is pulled out in one direction while the other is removed in the opposite direction.

Although we have described and illustrated our invention in considerable detail, we do not wish to be limited to the exact and specific details thereof as shown and described, but may use such modifications in, substitutions for, or equivalents thereof as are embraced within the scope of our invention, or as pointed out in the claims.

Having thus described our invention, what we claim and desire to secure by Letters Patent is:—

1. The steps in the method of forming a truck side frame, comprising taking a previously cut and edge flanged plate, placing its intermediate portion over a grooved die, then projecting a male die against the intermediate portion only of the plate and forcing said intermediate portion into said groove, whereby the side portions, adjacent the intermediate portion of said plate are bent towards and at an angle to each other, without contact of the dies therewith.

2. The steps in the method of forming a truck side frame, comprising taking a previously cut and edge flanged plate, placing the intermediate portion thereof over a die having a groove therein of open-box form, then projecting a registering male die

against the plate and forcing said intermediate portion thereof into said groove, whereby the side portions of said plate, adjacent said intermediate portion, are bent 5 toward and at an angle to each other with their corresponding flanges substantially opposite each other, without contact of the dies therewith.

3. The steps in the method of forming 10 a truck side frame, comprising taking a previously cut and edge flanged plate, placing its intermediate portion over a grooved die, then projecting against said portion a male die provided with a forming portion 15 removably attached to its edge, which contacts with said plate, then relatively moving said dies and forcing a portion of the plate into said groove, whereby the side portions of said plate are bent toward each 20 other, and then taking away the securing means of said removable portion, and withdrawing the male die.

4. The steps in the method of forming 25 a truck side frame, comprising taking a previously cut and edge flanged plate, placing a portion thereof over a grooved female die, then projecting against said portion a male die provided with a removable former consisting of a pair of wedge-shape 30 members adapted to contact with said plate, which together provide the desired shape, then relatively moving said dies and forcing a portion of the plate into said groove, whereby the sides of said plate are bent 35 toward each other with their corresponding flanges substantially opposite, then taking away the securing means of said removable former, then withdrawing the male die and then longitudinally removing the wedge-shaped members from the bent plate.

5. The steps in the method of forming 40 a truck side frame, comprising taking a previously cut and edge flanged plate, placing its intermediate portion over a grooved female die, then projecting against said portion a male die provided with a movable former wider than said latter die and adapted to contact with said plate, then relatively moving said dies and forcing a portion 45 of the plate into said groove, whereby the side portions of said plate are bent toward each other, then taking away the securing means of said former and withdrawing the narrower portion of the male die between

the bent portions of the plate and the flanges 55 thereof, which are opposite each other, but spaced apart.

6. Apparatus for forming flanged truck side frames comprising a female forming die having a longitudinally extending groove 60 therein of open-box form, a corresponding male die of lesser width adapted to register therewith, provided with grooves in its sides adapted to receive the flanges of the frame, a removable forming member of greater 65 width than said male die removably secured to the operating edge thereof, and means for relatively moving said dies in registry.

7. A forming die provided with an approximately rectangular groove therein of 70 open-box form with rounded corners, a corresponding male die of narrower width provided with a plurality of grooves therein adapted to receive the flanges of a plate to be bent, and a member of greater width 75 than the male die removably secured thereto.

8. A female forming die having a groove 80 therein of open-box form, a corresponding male die of lesser width than said groove adapted to register therewith, a removable forming member of greater width than said 85 male die composed of a pair of oppositely tapered portions removably secured thereto, and means for relatively moving said dies in registry.

9. The combination of a female forming die having a groove therein of approximately rectangular form with rounded corners, a corresponding male die of less width than said groove provided with a bifurcated 90 clevis member at each end, and a pin passing through each clevis in which is mounted a forming member of greater width than said male die.

10. The combination of a female forming 95 die having a groove therein of approximately rectangular form with rounded corners, a corresponding male die of less width than said groove provided with a bifurcated clevis member at each end, a pin passing through 100 each clevis in which is mounted a forming member of greater width than said male die, and composed of a pair of oppositely tapered members.

In witness whereof we hereunto affix our 105 signatures.

LINDSAY C. PRITNER.
HENRY C. DORRIS.
